UNITED STATES PATENT OFFICE.

JOHN ROGERS FLANNERY, OF PITTSBURGH, PENNSYLVANIA, ASSIGNOR TO FLANNERY BOLT COMPANY, OF PITTSBURGH, PENNSYLVANIA.

STAY-BOLT STRUCTURE.

1,276,746.

Specification of Letters Patent. Patented Aug. 27, 1918.

Application filed November 21, 1916. Serial No. 132,609.

To all whom it may concern:

Be it known that I, JOHN ROGERS FLANNERY, a citizen of the United States, and a resident of Pittsburgh, in the county of Allegheny and State of Pennsylvania, have invented certain new and useful Improvements in Stay - Bolt Structures; and I do hereby declare the following to be a full, clear, and exact description of the invention, such as will enable others skilled in the art to which it appertains to make and use the same.

This invention relates to improvements in stay bolt structures for boilers, the object of the invention being to provide simple and efficient means for detecting the condition of the bolts without necessity of removing said bolts from the boiler.

With this object in view, the invention consists in certain novel features of construction and combinations of parts as hereinafter described and pointed out in the claims.

In the accompanying drawings, Figure 1 is a sectional view of a stay bolt showing an embodiment of my invention, and Fig. 2 is a separate view of the detector.

In the embodiment of my invention shown in the drawing, 1 represents a stay bolt of the flexible type, the same having a spherical head 2 to be seated in a suitable bearing applied to the outer boiler sheet, as is well known in flexible stay bolt construction. In the drawing, I have shown the inner boiler sheet 3 through which the inner ends of the bolt is threaded,—the inner end of the bolt being shown as being upset as indicated at 4. While I have shown this type of stay bolt to exemplify my improvements, it will be understood that my invention is applicable to other type of stay bolts.

The stay bolt is provided with a bore, cavity or tell-tale hole 5 which, in the bolt shown in the drawing, may extend from its inner end to a point in proximity to its head 2, and in this hole or cavity, I insert a solid material, capable of being readily removed, and which is sensitive to the action of water, so that the contact of water therewith will cause a change in the appearance of the material.

In the embodiment of my invention shown

in the drawing, the material thus introduced into the hole in the bolt consists of a metal rod 6 having a threaded head or enlargement 7 at one end, which head may be screwed into a recess 8 which forms a slightly enlarged portion of the bore or hole in the bolt at the inner end thereof,—said head or enlargement 7 thus serving as a closure for the hole or bore in the bolt and also serving as means for the reception of a tool whereby the rod or detector may be removed. The rod or detector 6 may be made, for example, of a metal which will oxidize, corrode or become discolored by the action of water, such for instance, as ferrous metal, as iron or steel.

In the event of rupture or breakage of the bolt so that water would be permitted to enter the bore, cavity or tell-tale hole, contact of such water with the metal rod will cause the latter to become oxidized, corroded or discolored and thus indicate that the bolt is defective.

From the above, it will be apparent that in inspecting the bolts, the inspector may quickly ascertain the condition of the bolt by removing the metal detector and examining it. If he finds it to be normal in appearance, he will know that the bolt is good, but if he finds said detector to be oxidized, corroded or discolored, he will know at once that the bolt is defective.

Having fully described my invention, what I claim as new and desire to secure by Letters-Patent, is:—

1. A staybolt having a cavity readily accessible from one end of the bolt and closed at its other end within the bolt, and a removable detector located in and readily removable bodily from the accessible end of said bore, said detector being made of material which is sensitive to the action of water to denote the condition of the bolt.

2. A stay bolt having a bore closed at one end and open at the other end, and a metal rod removably disposed in said bore and removable through said open end thereof, said metal rod being such as shall be sensitive to the action of water to denote the condition of the bolt.

3. A stay bolt having a bore having one end closed within the bolt and open at the

other end, said open end of the bore being provided with a threaded portion, and a removable detector which is sensitive to the action of water to denote the condition of the bolt, within said bore, said detector having a threaded part at one end to enter the threaded part of the bore of the bolt.

Copies of this patent may be obtained for five cents each, by addressing the "Commissioner of Patents, Washington, D. C."

In testimony whereof, I have signed this specification in the presence of two subscribing witnesses:

JOHN ROGERS FLANNERY.
